UNITED STATES PATENT OFFICE.

JOSEPH EDGAR KING, OF NANTYFFYLLON, NEAR BRIDGEND, AND BENJAMIN MORGAN, OF CAERAU, NEAR BRIDGEND, WALES.

SAFETY-CLEVIS.

1,387,781.

Specification of Letters Patent. Patented Aug. 16, 1921.

Application filed July 6, 1920. Serial No. 394,264.

To all whom it may concern:

Be it known that we, JOSEPH EDGAR KING, residing at 21 Humfray street, Nantyffylon, near Bridgend, South Wales, and BENJAMIN MORGAN, residing at 18 Glenavon Terrace, Caerau, near Bridgend, South Wales, subjects of the United Kingdom of Great Britain and Ireland, have invented a new and useful Safety-Clevis, of which the following is a specification.

Our invention relates to improvements in shackles or couplings for connecting cars, used for the conveyance of minerals in mines, in which a movable pin forms the vertical part of a D link, the engagement or disengagement of the shackle being performed by the lowering or lifting of the said pin respectively; and the objects of our improvements are first, to prevent the accidental lifting of the pin by providing a locking device in the lower eye of the shackle acting in conjunction with a special form of annular recess on the base of the pin; second, to secure rapid disengagement of the shackle by allowing the pin to be lifted in all positions; and third, to allow of adjustment for any wearing of the parts that may take place. The D link may be used in connection with another of like construction, an oval ring, or a drawbar. We attain these objects by means of the mechanism illustrated in the accompanying drawings, which refer to the D link, only, in which,

Figure 1 is an elevation of the D link complete (half full size).

Fig. 2 is a view of the lower eye of the shackle from underneath with the mechanism in place.

Fig. 3 is an end elevation of the D link with the eyes in section.

Fig. 4 is a view of the base-plate.

Fig. 5 is a view of the rivets which hold the locking in place.

Fig. 6 is a view of the flat springs.

Fig. 7 is a view of the part of the lock and of the adapters.

Fig. 8 is a view of the spiral springs.

The pin 1 provided with a link 2 for lifting, works freely in the round eyes of the D link 3, and is prevented from rising too high by the projection 4. The base of the pin is recessed at 5, and tapered at 6.

The lower portion of the eye 7, is bored to receive the lock 8. The lock 8 consists of two halves, which when assembled are square shaped with projecting rounded

shoulders 9 at each corner. These shoulders 9 are bored and tapped to receive the adapters 10. Spiral springs 11 draw the parts of the lock 8 together, and these springs 11 are threaded through holes in the shoulders of the hollow adapters 10, which have right and left-handed screw threads respectively as shown. These springs 11 work in the grooves 12, at the sides of the lock 8. In the center of the lock 8 is an elliptical opening, countersunk from both sides to fit the recess 5 on the pin 1. Flat friction springs 13, bent as shown, working on the rivets 14, (which are shouldered to avoid projecting beyond the case 7) and guided by the spindles 15, assist in keeping the lock 8 closed in the proper position. The lock is held in place by means of two riveted spindles 15, which pass through the adapters 10, and the spiral springs 11. The opening at the bottom of the eye 7 is closed by a screwed plate 16, with an opening in the center countersunk to fit the taper 6 on the pin 1. Recesses 17 are provided for easy opening, while the set screw 18 keeps the plate 16 in place.

We are aware that prior to our invention, D links for shackles have been made with a movable pin forming the vertical part of the D link.

We therefore do not claim such a combination broadly, but we claim:—

1. The combination, in the D links of a shackle for mine cars, of the recessed and tapered pin 1, with the bored and countersunk lock 8, housed in the lower eye 7 of the shackle, substantially as specified.

2. In a shackle the combination of the adapters 10, to which are fixed the spiral springs 11, with the lock 8, substantially as described.

3. In a shackle the combination of the flat friction springs 13 with the lock 8, substantially as described.

4. The D link of a shackle having a recessed and tapered pin 1, coacting with a bored and countersunk lock 8 which is normally kept closed by the spiral springs 11, and the adapters 10, and kept in position with the assistance of the friction springs 13.

JOSEPH EDGAR KING.

BENJAMIN ^{his} ~~mark~~ MORGAN.
